(57) **CLAIM**

The ornamental design for a handpiece for high frequency treatment device, as shown and described.

DESCRIPTION

FIG. 1 is a top perspective view of a handpiece for high frequency treatment device;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1; and,

FIG. 9 is an enlarged view of the encircled portion 9 in FIG. 1.

The broken lines in the drawing depict portions of the tip for high frequency treatment device and form no part of the claimed design. The dot-dot-dash broken lines encircling enlargement portions of the claimed design form no part of the claimed design.
